(57) **CLAIM**

The ornamental design for a pocketed cover for a chair, as shown and described.

DESCRIPTION

FIG. 1 is an isometric view of a pocketed cover for a chair showing my new design;

FIG. 2 is a front view thereof;

FIG. 3 is a right side view thereof;

FIG. 4 is a back view thereof;

FIG. 5 is a left side view thereof;

FIG. 6 is a top view thereof; and,

FIG. 7 is a bottom view thereof.

The portions of the drawings shown in broken lines represent environmental structure and form no part of the claimed design.

1 Claim, 5 Drawing Sheets

FIG. 1.

FIG. 2.

FIG. 3.

FIG. 4.

FIG. 5.

FIG. 6.

FIG. 7.
